UNITED STATES PATENT OFFICE

WILLIAM E. WINE, OF TOLEDO, OHIO

CAR LADDER

Original application filed April 16, 1928, Serial No. 270,303. Divided and this application filed April 17, 1929. Serial No. 355,842.

My invention relates to new and useful improvements in car ladders, and the present application is a division of the application filed by me on April 16, 1928, bearing Serial No. 270,303, and entitled "Car ladders".

One of the objects of the present invention is to produce an all metal ladder comprising stiles made out of angle iron with the holes in the opposite faces of each angle iron so that after the rungs are placed in position and the stiles set, no further fastening for the rungs is necessary.

In its broadest aspect it is similar to the ladder shown in the patent granted to me on February 13, 1917, numbered 1,215,455.

The present invention, however, contemplates the use of two brackets designed to be fastened to the sides of a car or other structure, and to secure to the opposite ends 20 of the stiles a form of bracket which latter are designed to cooperate with the said brackets on the car, so that the ladder as an entirety, may be quickly hung and bolted into place, or just as quickly removed.

Still another object of the invention is to provide a car ladder that may be easily and quickly fabricated or assembled and wherein the brackets may be quickly applied to a freight car, after which the ladder may be 30 quickly hung and bolted in place so that the cost of installation is greatly reduced.

Still another object of the invention is to so construct a ladder which may be quickly and easily installed, that if for any reason 35 it should become damaged in service, it is but a simple matter to remove the old ladder and replace it with a new one.

With these and other objects in view, the invention consists in certain new and novel 40 arrangements and combination of parts as will be hereinafter more fully described and pointed out in the claims.

Referring now to the drawings showing a preferred embodiment of the invention,

Fig. 1 is a fragmentary side elevation of a car showing a ladder on the side of the car and a ladder on the end of the car.

Fig. 2 is an end elevation showing the two ladders in place.

Fig. 3 is a fragmentary enlarged lower end

view of one of the styles, showing a part of a rung and the fastening means for the stiles.

Fig. 4 is a sectional view taken on line 4-4 of Fig. 3.

Fig. 5 is a similar view, the bracket and rung being left out for the sake of clearness.

Fig. 6 is a horizontal sectional view, one-half being taken through the bracket, and the other half being taken through the rung.

Fig. 7 is a perspective view of the lower end of the stile, and

Fig. 8 is a perspective view of the bracket which cooperates with the lower end of the stile.

Referring more in particular to the several views, there is shown in Fig. 1 the fragmentary end 1 of a hopper car, and secured by brackets, (to be hereinafter described) is the ladder 2 which extends from the top of the car down to the side sill 3.

There may also be seen a ladder 4 fastened to the end of the car, while beneath the ladder 2 may be seen the usual step 5. It will also be seen that the ladder comprises the two stiles 6 and 7, which are identical, so a description of the one will be a description of the other.

Describing, therefore, in detail one of these stiles there will be seen a metal angle iron which is provided in the present illustration, with four sets of holes in the two faces, one hole of each set being opposite the hole of the other.

In Fig. 7 a set of these holes may be seen, one in the one face of the angle and the other 85 hole in the opposite face.

In my earlier patent, above referred to, I simply made these holes circular in shape, but I have found that by flattening out the sides 9 of the openings I accomplish two functions that I did not accomplish in my earlier construction.

The manner in which I form the ends of the rung to fit within the respective holes of the stiles and the way in which I offset the rungs is the subject matter of the parental application, so that in this application I will only describe briefly the specific construction of the ends of the stile and the manner of securing them in position.

Looking at Figs. 3, 4 and 6, it will be seen that the rung 10 is offset, as at the point 11, then flattened, as at 12, and again bent, as at 13. The rung then projects outwardly, as at 14, while the front and rear faces are flattened, as at 15 and 15a. The face 15a is slightly inclined to the axis of the rung, so that it will clear the flattened side wall 9 when the rung is inserted.

To insert the rung 10 in the stile, it is only necessary to place the end in one face of the angle and move it through the opening until the end 14 passes outwardly through the other opening or hole 9, and in the same manner pass the opposite end of the rung through the other stile, as will be readily understood. By flattening the ends of the rung and making the holes rectangular in shape, it allows me to use a thicker rung without drilling larger holes in the stile.

This part of the invention, as heretofore mentioned, forms the subject matter of the parental application.

Referring now to the gist of the invention, that is the manner of applying the ladders to the cars or other structures, and referring to Figs. 3 to 8 inclusive, and particularly to Fig. 7, it will be seen that the stile 6 has on one of its faces a form of bracket 16 which comprises a piece of metal having the one face 17 which is bent over on itself to form the face 18 and to also form the space 19 which will receive the end 20 of the car bracket 21 as will be shortly described. This bracket 16 or tongue is riveted as at 22 to the inner face of the stile, and is substantially the width of one of the faces of the stile, so that the inner edge of the bracket will lie flush with the adjacent face of the stile.

It will be noted, however, that this bracket 16 is also cut away along its inner edge as at 23, which is in the same plane with the lower edge 24 of the inner face 17 of the bracket. Just below the rivet 22, there is another hole 25 directly opposite a hole 26 in the face of the stile so that when the stile is placed in the position as shown in Fig. 3, the end 20 of the bracket will fit within the space 19 and the lip 27 on the end 20 of the car bracket 21 will fit in the cut out portion 23 to thus support and hold the stile, as will be readily understood.

There are two of these car brackets 21, preferably metal strips, and both have their opposite ends bent as just above described. One of these brackets is placed near the upper part of the car and one down by the side sill. It will also be understood that there is a bracket 16 on the upper end of the stile so that when the ladder is placed in position, the four brackets 16 will fit over the four ends of the two car brackets 21. The bolts 28 will then be passed through the stiles and the brackets 16 and through the bolt holes 29 in the ends 20 of the bracket 21, and thus se-

curely lock the ladder as a whole to the car side or end. The bolts 28 will have square heads and will fit up against the lips 27 to be thus held against turning when the nuts are applied to the bolts.

Thus it will be seen that after the brackets 21 are securely riveted to the car sides or car ends, the ladder being previously assembled, will simply be placed slightly above the bracket and then pulled down into place so that the brackets 16 will also engage the respective ends of the brackets 21, after which the bolts 28 will be tightened into position.

If at any time it is desired to remove the ladder, the bolts 28 are simply removed and the ladder lifted slightly off the bracket and then bodily removed.

From the foregoing it will be seen that I have provided an extremely efficient form of ladder wherein the rungs may be quickly slipped within the stiles and after the car brackets are placed in position on the ends and sides of the car, the ladders may be placed in position so that the small brackets on the ends of the stile interlock with the brackets on the car and after which the few bolts may be placed in position to rigidly tie the ladder to the car.

The ladder is relatively light in weight, and the many thousands of ladders now in use are proving very efficient.

Many slight changes might be made without in any way departing from the spirit and scope of the invention.

Having thus described my invention, what I claim as new and desire to secure by Letters Patent is:

1. A car ladder comprising stiles and rungs, a bracket secured to the upper and lower ends of said stiles, each of said brackets comprising a member turned back on itself, said turned back portion terminating short of the lower end of the front part of the member, the said member having an inner edge cut away in a line flush with the lower edges of the turned back portion of the member, and two cooperating brackets adapted to be fastened to a car and have their ends interlocked within the said brackets on the stiles.

2. In a car ladder, angle iron stiles, a bracket riveted within the angles, each of said brackets comprising a member turned back on itself, and said turned back portion terminating short of the lower end of the front part of the member, the turned back portion lying flush with a leg of the stile to thereby form a space between the leg of the stile and the outer portion of said bracket, the inner edge of the outer portion of the bracket being cut away to form a notch extending flush with the turned back portion, and said brackets adapted to interlock with a car bracket.

3. A car ladder comprising in part angle iron stiles, brackets in the angles of the stiles, each of said brackets comprising a member

turned back on itself, said turned back portion terminating short of the lower end of the front part of the member, the inner edge of the front portion being cut-away in a line flush with the lower end of the turned-back portion, a car bracket having each end bent at right angles and provided with a further lug parallel with the axis of the bracket, the ends of the car brackets fitting under the brackets on the stiles and interlocking therewith, and means for further locking the stiles and brackets to the car brackets.

4. A car ladder comprising angle iron stiles and rungs, brackets within the angles of the stiles, each of said brackets having a portion spaced from both the legs of the stile, car brackets to respectively engage the brackets on the stiles and fill up the spaces between the two respective legs of the stiles, and means for locking the stiles to the car brackets.

5. A car ladder comprising angle iron stiles, brackets secured in the angles of said stiles, each of said brackets comprising a tongue and turned-back portion which terminates short of the lower end of the front part of the member, the turned-back portion lying flush with one angle of the stile, the edge of the tongue lying adjacent the other angle of the stile and being cut away to a point flush with the lower edge of the turned-back portion, a car bracket fitting in the resultant spaces formed in the bracket, and means for locking the car bracket to the bracket of the stile.

6. A freight car ladder comprising angle iron stiles and rungs, brackets near the four corners of the stiles, each of said brackets comprising a tongue having its edge cut back, cooperating car brackets fitting behind the tongue and in the space formed at the edge of the tongue and further means for holding the cooperating parts together.

In testimony whereof I affix my signature.
WILLIAM E. WINE.
